MECHANICAL SIGN

George Gordon, Sacramento, Calif.

Application July 18, 1939, Serial No. 285,059

8 Claims. (Cl. 40—33)

This invention relates generally to an improvement in outdoor advertising or display signs, and in particular the invention is directed to an improved mechanical or animated sign.

The principal object of the invention is to provide a mechanical sign including body or housing adapted to carry an advertising sign or symbol and mounted for movement through a predetermined path; there being members which represent an animate object, such as the wings of a bird, projecting from said body or housing and mounted for movement to simulate the natural movement of the animate object represented thereby.

Another object of the invention is to provide a mechanical sign of the type described which includes in combination with a supporting tower assembly, a novel drive means arranged to effect not only the movement of the body or housing through a predetermined path but also to simultaneously and without separate drive means, to accomplish the movement of the members which represent the animate objects.

A further object of the invention is to provide a mechanical sign of the type described wherein the body or housing and the attached movable members may be used without the tower assembly, and in such event the movable members are driven through the medium of separate means included in part in said body or housing.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views:

Figure 1 is an elevation of the device; the lower portion of the tower and a portion of the base being broken away to show the enclosed drive mechanism.

Figure 2 is an enlarged fragmentary sectional elevation of the gearing assembly at the top of the tower.

Figure 3 is a front elevation of the movable body or housing; the cover plate being removed.

Figure 4 is a cross-section on line 4—4 of Fig. 3.

Referring now more particularly to the characters of reference on the drawings, the device comprises a hollow base 1 having a hinged door

2 on one side thereof. A vertical and hollow tower 3 is mounted on top the base and preferably tapers somewhat from bottom to top as shown. A tubular post 4 is mounted on the base in vertical position and extends therefrom within the tower to its upper end; the upper end of the post terminating some distance above the adjacent end of the tower.

Vertical drive shaft 5 is disposed in the post and extends from a point in the base 1 to a point adjacent but beyond the upper end of said post; such shaft being carried in the post by journals such as shown at 6. A motor 7 is mounted in the base and is connected in driving relation with the lower end of vertical shaft 5 by suitable drive mechanism indicated generally at 8.

The projecting portion of post 4 at the upper end of tower 3 supports a fixed, horizontally disposed and upwardly facing bevel gear 9. A horizontal head 10 is keyed on shaft 5 immediately above gear 9, and opposed horizontal shafts 11 and 12 are rotatably seated at their inner ends in bores 13 and 14 respectively in said head. Pinions 15 and 16 are carried by shafts 11 and 12 and mesh with the fixed gear 9; pinion 15 being free on its shaft while pinion 16 is keyed on shaft 12. Shaft enclosing sleeves 17 and 18 surround shafts 11 and 12 and said sleeves are supported in non-turnable position by means of brace arms 19 which extend upward in diverging relation from a rotatable collar 19a on the top of the tower. The assembly including gear 9 and meshing pinions 15 and 16 are enclosed within a suitable case 20.

Counterbalance 21 depends from sleeve 17 outwardly of the corresponding brace arm 19, and such counterbalance is preferably constructed of sufficient vertical surface area to carry advertising matter. The outer end of sleeve 18, which surrounds shaft 12, is fixed with one edge of a body or housing 22 adjacent the upper end thereof by means of an attaching bracket 23. This housing forms a support for the movable sign elements hereinafter described.

In order to accommodate the requisite mechanism, housing 22 increases in width from top to bottom while having a constant thickness. One face of this housing is in the form of a removable plate 24.

The outer end of shaft 12 projects from sleeve 18 into housing 22 and at such end is provided with a fixed pinion 25 which meshes with a bevel gear 26 mounted on one end portion of a horizontally disposed crank shaft 27 journaled between the side plates of a rectangular and elongated

gated supporting frame 28 in the housing. A connecting rod 29 on and depending from the crankshaft is pivoted at its lower end at 30 on the upper end of a vertically movable bar 31 which projects through guides 32.

Opposed sign forming elements 33 which represent animate objects—such as wings of a bird—are pivoted on a common axis 33a on frame 28 and which axis 33a is parallel to that of crankshaft 26; said elements 33 being of substantial length and projecting through slots 34 in the housing. A cross arm 35 is fixed intermediate its ends on bar 31 above pivot 33a, and pivoted links 36 are connected between the outer ends of said cross arm and the corresponding elements 33 at a point outwardly of pivot 33a.

In use, advertising matter or symbols are affixed on both faces of the housing 22 and, as will be obvious, operation of the motor 7 causes the housing to be carried about horizontally in a circle and at the same time the elements 33 recurringly and simultaneously rise and fall in simulation of the movement of a bird's wings.

In the event that it is desired to mount the housing 22 in a fixed position rather than movable as described above, the tower and its associated driving assembly are omitted and the crankshaft 26 actuated from a pulley 37 mounted on the end thereof opposite gear 26; such pulley being adapted to be driven from a motor by an endless belt (not shown) which extends through a slot 38 in the bottom of housing 22.

My improved mechanical sign is one which will attract the attention of persons passing by the same, and thus is an excellent medium for advertising purposes.

While the structure has been particularly designed for use as a commercial sign, it may also be put to other uses, or be made as a toy.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention, what I claim as new and useful and desire to secure by Letters Patent is:

1. In a mechanical apparatus, a support, an element, means for mounting the element upon the support for movement in a predetermined path, a shaft, means rotatably mounting said shaft at one end on the support, driving connections between said end of the shaft and the movable element, separate means supporting the shaft adjacent its other end for movement in a path at substantially right angles to the path of movement of the element, and drive means arranged to simultaneously rotate said shaft and move same in its path of movement.

2. A device as in claim 1 in which said separate means includes a vertical tower; the shaft projecting substantially horizontally from the upper end of said tower.

3. A mechanical sign comprising a substantially vertical tower, a shaft, means rotatably mounting the shaft adjacent one end on the upper end of the tower in a substantially hori-

zontal and projecting position and for swinging movement horizontally in an arcuate path, a support depending from the other end portion of the shaft, a sign element, means mounting the sign element on the support for up and down movement in a substantially vertical plane, driving connections between the element and the adjacent end of the shaft, and drive means associated with the tower and arranged to simultaneously rotate the shaft and swing the same in said path.

4. A device as in claim 3 in which said drive means comprises a bevel gear fixed on the tower in horizontal position, a pinion secured on the adjacent portion of the shaft and meshing with said bevel gear, a rotatable member disposed inwardly of the pinion and with its axis aligned with that of the bevel gear, the shaft projecting inwardly from the pinion, the member having a radial socket in which the projecting portion of the shaft is rotatably seated, and drive means to rotate said member.

5. A mechanical sign comprising a substantially vertical tower, a shaft journaled in said tower and extending to the top thereof, means to rotate said shaft, an upwardly facing bevel gear fixed on the upper end of the tower, a head of less diameter than the gear fixed on the upper end of the shaft and disposed adjacent but above the bevel gear, the head having a radial socket therein, a substantially horizontal shaft rotatably seated in the socket and projecting some distance from the tower, a pinion fixed on the shaft and meshing with the bevel gear, a support depending from the outer end of the shaft, a sign element mounted on the support for movement relative thereto, and driving connections between the shaft and said element.

6. A device as in claim 5 in which the head is formed with another and opposed radial socket, another shaft rotatably seated in said other socket and projecting therefrom, an idler pinion on said other shaft and meshing with the bevel gear, and a counterbalance depending from the projecting portion of said other shaft.

7. In combination, a shaft supported at one end and mounted for swinging movement in a predetermined path, a support depending from the other end portion of the shaft, an element formed to represent an animate object, means mounting said element on the support for relative movement in a predetermined path, driving connections between said element and the adjacent end of the shaft and a drive mechanism operatively connected with the shaft and arranged to simultaneously rotate said shaft and move same in its path of movement.

8. In combination, an upstanding tower, a shaft projecting from the tower adjacent its upper end, means rotatably mounting the shaft at one end on the tower for swinging movement in a predetermined path, a support depending from the outer end portion of the shaft, an element formed to represent an animate object, means mounting said element on the support for relative movement in a predetermined path, driving connections between said element and the adjacent end of the shaft, and a drive mechanism associated with the tower and connected with the shaft to simultaneously rotate said shaft and move same in its path of movement.

GEORGE GORDON.
